DESIGN FOR AN EGG BEATER OR SIMILAR ARTICLE

Charles A. Rowley, Los Angeles, Calif.

Application December 13, 1937, Serial No. 73,590

Term of patent 14 years

To all whom it may concern:

Be it known that I, Charles A. Rowley, a citizen of the United States, residing at Los Angeles, in the county of Los Angeles and State of California, have invented a new, original, and ornamental Design for an Egg Beater or Similar Article, of which the following is a specification, reference being had to the accompanying drawing, forming part thereof.

Fig. 1 is a front view in elevation of the egg

beater or similar article embodying my design; Fig. 2 is a view in side elevation of the same; Fig. 3 is a sectional view taken substantially upon the line 3—3 upon Fig. 1.

The dominant feature of my design is shown in full lines.

I claim:

The ornamental design for an egg beater or similar article, as shown and described.

CHARLES A. ROWLEY.
